S. AND F. PELC.

CANE GUN.

APPLICATION FILED JUNE 18, 1919.

1,320,493.

Patented Nov. 4, 1919.

UNITED STATES PATENT OFFICE.

STEFANIA PELC AND FRANK PELC, OF McDONALD, PENNSYLVANIA.

CANE-GUN.

1,320,493.

Specification of Letters Patent.

Patented Nov. 4, 1919.

Application filed June 18, 1919. Serial No. 305,027.

To all whom it may concern:

Be it known that I, STEFANIA PELC, a citizen of Poland, residing at McDonald, county of Washington, and State of Pennsylvania, and I, FRANK PELC, a citizen of Poland, residing at McDonald, county of Washington, and State of Pennsylvania, have invented certain new and useful Improvements in Cane-Guns, of which the following is a specification.

This invention has as its object the provision of a pistol combined with a cane in such manner as to be normally unobservable, but which may be separated from the cane and used as a fire arm in a convenient and practical manner.

These and other objects, which will become more fully apparent as the description progresses, are attained by the novel construction and combination of parts herein-after described and shown in the accompanying drawings, forming a material part of this disclosure and in which—

Figure 1 is a partial side elevational view showing a combined gun and cane made in accordance with the invention, parts being broken away in order to disclose the interior construction.

Fig. 2 is a longitudinal sectional view taken on line 2—2 of Fig. 1.

Fig. 3 is a transverse sectional view taken on line 3—3 of Fig. 1.

Fig. 4 is a similar transverse sectional view taken on line 4—4 of Fig. 1, and

Fig. 5 is a side elevational view showing the implement complete.

Referring to the drawings, the numeral 10 indicates the cane or staff element, here shown to be slightly conical and terminating 40 in a tip 11, adapted to make contact with the ground when the device is used as a cane.

The upper end of the cane body 10 contains a recess 12, from which leads a screw-threaded opening 13, receptive of a threaded 45 stem 14, formed with the body 15 in which the gun-lock mechanism hereinafter to be described is contained. The body 15 has a similar screw-threaded extension 16 at the opposite end on which is engageable the cap 50 element 17 of the cane.

Slidably engaged with the cylindrical body 15, is a tubular casing 18 normally held in a raised or upward position, as shown in Fig. 5, by a bayonet joint device 55 19, the same engaging with a pin 20, set in

the body, a similar pin 21 being secured in the lower portion of the body, engageable with a like slot 19' formed in the opposite or lower end of the slidable casing 18.

A front sight 22 is engaged in a longitudinal recess 23, formed in the threaded extension 14, the sight base being hingedly engaged by a pin 24 and held in either of its adjusted positions by a flat spring 25, fixed in the bottom of the recess 23.

Similarly a rear sight 26 is hingedly engaged by the pin 27, and held in either of its adjusted positions by a flat spring 28, secured in the recess 29, formed midway in the body, the front sight being obscured when 70 inclosed in the upper end of the cane element 10, while the rear sight 26, when the device is used as a cane, is covered by the sliding tubular casing 18.

Extending axially into the body, and 75 through the extension, is a gun barrel 30 through which the bullets are discharged, the inner end of the barrel communicating with a chamber 31, open at one side and receptive of a pair of projections 32 formed 80 with a plate 34, having extending lugs 35 and 36, suited to the exterior of the body 15.

Projecting rearwardly from the rear lug 36 is an arm 37, pivoted on a pin fixed in the body of the gun. An opening is drilled 85 longitudinally in the lugs 35 and 36 adapted to receive a pin 38, to which is attached a finger clip 39 adapted to be operated so as to retract the detent point 40, formed with the end of the pin 38 and having an angular 90 end, the detent being engageable with the body 15 so as to hold the cartridge carrying projections 32 in proper position when closed, the detent being projected outwardly 95 so as to remain locked by a coiled compression spring 41, extending between the lug 36 and finger clip 39.

Entering into the center of the chamber 31 is a passage 42, communicating with an axial cylindrical opening 43, extending outwardly 100 through the entire length of the body and projection 16, the projection having an internal thread 44, receptive of a plug 45 compressing a spring 46 against the firing pin 47, the point 48 of which is adapted to pass 105 through the opening 42 and make contact with the cartridge 33 carried between the projections 32 in the chamber 31, a stem 49 projecting from the firing pin, opposite to the point 48, so as to guide the spring 46. 110

Extending out from the firing pin head 47 is an arm 50, operating in a slot 51, extending from the bore 43 outwardly through the body 15, and pivoted in the outer end of the arm, on a pin 52, is a trigger element 53, containing a nail notch 54, by which it may be raised from the recess 55 formed in the side of the body 15, the trigger element 53 being normally folded so as to extend parallel with the firing pin body 47 within the recess so as to permit the casing 18 to be moved thereover.

Extending outwardly from the firing pin head 47, opposite the arm 50, is a lug 55, having a beveled rear surface and adapted to depress the correspondingly beveled end 56 of a lever arm 57, pivoted on the pin 58, the rear element 59 of the lever being provided with a projection 60, terminating in a knob 61 contained within the recess 62, formed in the body 15 near its outer end. The lever is normally pressed into engaging position by a flat spring 63 contained within an internal recess 64, formed in the body 15 and leading out from the central bore 43.

In operation, when it is desired to use the implement as a gun, the body portion 14, is unscrewed from the cane shank 10, prior to which the tubular casing 18 is disengaged from the pin 20 and engaged with the pin 21 whereupon the sight 26 may be raised by the fingers so as to extend above the surface of the casing 18, and the hingedly engaged element 53 of the trigger is turned outwardly so as to be engaged with the finger; the firing pin block 47 is retracted, pressing the spring engaged by the detent element 56, in which condition the gun is in condition to be discharged. The cartridge receiver is then moved outwardly by operating the extending element 39, a cartridge placed therein and the door-like structure closed, whereupon, by pressing the plunger knob 61, the firing pin is released and is forced forward by the spring 46, detonating the cartridge 33 in an obvious manner, whereupon the casing 18 may be moved so as to engage with the pin 20 and the apparatus

used in the manner of an ordinary walking cane.

Having thus described our invention and set forth the manner of its construction, application and use, what we claim as new and desire to secure by Letters Patent, is—

1. A gun comprising a cylindrical body, a sleeve slidable thereover, means for securing said sleeve at either end of said head, a gun barrel secured axially in said body, said barrel terminating in a chamber, a swinging cartridge carrier enterable into said chamber, means for securing said cartridge carrier when entered, a plunger having a firing point adapted to engage with a cartridge in said carrier, means for projecting said plunger forward, means for manually retracting said plunger, a detent engageable therewith whereby said plunger may be held when in a retracted position, a release for said detent and a pair of sights arranged in said body, said sights being adjustably positioned, either vertically or horizontally, and a cane shank to which said body may be engaged.

2. In a cane gun, the combination with a staff having a threaded upper end, and a body engageable therewith, of a casing slidable on said body, a barrel disposed axially in one portion of said body, said barrel communicating with a chamber in said body, a pair of sights hingedly engaged and adapted to be raised or lowered, means for holding said sights when in an adjusted position, a cartridge carrying element hingedly engaged with said body adapted to enter the mentioned chamber, a firing pin, means for projecting said firing pin forward, means for manually retracting said firing pin, means for holding said firing pin when in a retracted position, and means for releasing said holding means whereby the cartridge may be discharged through said barrel when said body is disengaged from the cane staff.

In testimony whereof we have affixed our signatures.

STEFANIA PELC.
FRANK PELC.
